(57) CLAIM

The ornamental design for a charger, as shown and described.

DESCRIPTION

In a preferred form, the nature of this product is as a battery charging unit.

FIG. 1 is a left, top, front perspective view of a charger embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a rear elevational view thereof; and,

FIG. 6 is bottom plan view thereof.

The broken line representations in the figures are for the purpose of illustration only, and form no part of the claimed design.
